UNDERWATER BREATHING APPARATUS

Dudley B. Rose, Madison, Ohio

Application April 3, 1957, Serial No. 650,520

4 Claims. (Cl. 128—142)

This invention relates to self-contained underwater breathing apparatus.

An object of the present invention is to provide a self-contained underwater breathing apparatus which operates on the demand principle with a minimum of effort required for both inhalation and exhalation.

Another object of the present invention is to provide a self-contained breathing apparatus having a diaphragm actuated inhalation demand valve and an exhalation valve mounted in a common body which is closely associated with the mouthpiece of the apparatus whereby the external hydrostatic pressure on the diaphragm and the exhalation valve is the same as the internal pressure in the mouthpiece due to their relative location thereby eliminating all differential hydrostatic head pressures and subjecting the mouth of the user to the same internal and external hydrostatic pressure, when in use, thereby permitting relatively effortless breathing by the user of the apparatus.

Still another object of the present invention is to provide a novel breathing apparatus which operates on the demand principle and requires but a single small durable medium pressure conduit between the source of air or other fluid and the breathing apparatus which is effective in eliminating mouthpiece "pull" due to hose buoyancy, "water-drag" due to hose bulk and "corrugations" and is less vulnerable to hose fouling, snagging and puncturing.

A further object of the present invention is to provide a novel breathing apparatus having a diaphragm actuated demand valve and an exhalation valve mounted in a housing closely associated with a mouthpiece, wherein the volume of said housing is so small that substantially all breath is expelled at each exhalation and there being little or no building up of carbon dioxide and re-breathing it during inhalation.

Still another object of the present invention is to provide a novel breathing apparatus having a diaphragm actuated demand valve and an exhalation valve provided in the zone of the mouthpiece of the breathing apparatus wherein three-way equalization of essential pressures, namely pressure at demand valve diaphragm, pressure at exhalation valve, and pressure at mouth, permits uniform effortless breathing at any depth or position of the user due to the elimination of differential hydraulic head pressure between the above locations.

Another object of the present invention is to provide a novel breathing apparatus which operates on the demand principle and is characterized by its structural simplicity, the ease of assembly of its parts, its strong and sturdy nature and its low manufacturing cost. Other features of this invention reside in the arrangement and design of the parts for carrying out their appropriate functions.

Further objects of the present invention and certain practical advantages will be referred to in or will be evident from the following description of two embodiments

2

ments of the invention, as illustrated in the accompanying drawings in which:

Fig. 1 is a perspective view of the mouthpiece and its associated valve housing shown connected through a single conduit and a suitable control valve to a source of air or other fluid.

Fig. 2 is a vertical sectional view of the mouthpiece and valve housing of the present invention and showing the inhalation or demand valve in a closed position.

Fig. 3 is a vertical sectional view of the present invention similar to that of Fig. 2, but showing the diaphragm expanded and the inhalation or demand valve in an open position.

Fig. 4 is a top view of the diaphragm cover which serves to protect the diaphragm against foreign objects and further to clamp and seal the diaphragm to the valve housing of the present device.

Fig. 5 is a vertical transverse sectional view taken along the plane of line 5—5 of Fig. 3 and looking toward the exhalation valve of the present device.

Fig. 6 is a front elevational view of another embodiment of the present invention employing a circular housing and diaphragm.

Fig. 7 is a vertical section view of the breathing device shown in Fig. 6 taken along the plane of line 7—7 of Fig. 6.

Fig. 8 is a top plan view of the diaphragm used in connection with the embodiment of the present invention disclosed in Fig. 6.

Fig. 9 is a vertical cross-sectional view taken along the plane of line 9—9 of Fig. 8.

Fig. 10 is a vertical cross-sectional view similar to that in Fig. 7 but showing the diaphragm flexed inwardly and the demand or inhalation valve in an open position, and

Fig. 11 is an enlarged fragmentary sectional view of the demand valve disclosed in the embodiment of Figs. 6 through 10.

Before describing in detail the herein disclosed embodiments of the invention, it is to be understood that the present invention is not limited to the structural details or the particular arrangement of parts herein shown as devices embodying the present invention may take other forms. It also is to be understood that the phraseology and terminology herein used are for purposes of description and not of limitation, as the scope of the present invention is denoted by the appended claims.

Referring now to Fig. 1, the breathing apparatus in general will be seen to include a housing 10 having a chamber for a diaphragm and an exhalation and inhalation valve. A mouthpiece 11 is closely associated with the housing and has a single medium pressure hose 12 communicating between the inhalation valve of the mouthpiece and a source of air or other fluid container 13. The air container 13 is provided with a suitable manually operable control valve 14 by which the pressure in the hose may be readily and accurately regulated.

It will be understood that the air container 13 is normally provided with a suitable harness, not herein shown, whereby it may be supported on the body of a person using the apparatus. The air source here comprises a container or bottle of cylindrical form 13 and a pressure control valve 14 which may be of any suitable form and its sole purpose is to control the pressure in the connecting hose or conduit 12. The pressure reducing valve is attached to the tank by means of a suitable yoke attachment 15.

With reference now to Figs. 2 and 3 the novel self-contained underwater breathing apparatus comprises a mouthpiece 11 preferably constructed of a soft rubber or plastic material and a main body or housing 10 prefer-

ably constructed of a durable metal or hard plastic material which will resist wear and breakage. The central portion of the housing 10 is substantially rectangular in form having rounded ends and forms a chamber 16, as seen in Figs. 2 and 3. The chamber 16 is open at its front or top end as seen in Figs. 2 and 3 and is provided with suitable ports 17 and 18 which communicate through the mouthpiece with the mouth of the user, when in use. The right end of the housing 10 is provided with a hollow cylindrical shaped extension 10a which contains an inhalation or demand valve. The cylindrical extension 10a is threaded internally at 19 and threadedly receives a tubular socket 20 in its outer end. A tubular member 21 is adapted to be slipped into the socket 20 and is provided with a circular rim 22 which is peened down over the inner end of the tubular socket 20 so as to permit the tubular plug to be rotated freely within the tubular socket 20. An O-ring seal 23 is carried within a suitable groove provided in the tubular member 21 and engages the inner surface of the tubular socket 20 so as to provide a seal between the member 21 and the socket 20. An elbow fitting 24 threadedly engages the tubular member 21 adjacent its outermost end in such a manner that the tubular member 21 rotates in response to the movement of the elbow fitting 24. A suitable nipple 25, as seen in Fig. 1, is secured to the elbow 24 and is adapted to engage the end of the flexible hose 12 with this construction therefore, it will be realized that the elbow 24 will swing with the tubular member 21 and thereby follow the movement of the hose 12 and/or the housing 10 such that said hose does not become crimped or otherwise fouled, thus preventing any interruption in a fluid input flow from the container 13.

The tubular member 20 is provided with an inlet fluid port or passage 26 at its innermost end which communicates fluid between the hose 12 and the chamber 16 of the housing 10. A valve seat 27 is formed on the upstream face of the port 26 and is adapted to be engaged by a tilting demand valve body member 28 for opening and closing the inlet fluid port 26. The demand valve body 28 is provided with a valve stem 29 which extends in axial alignment through the center of port 26 so as to permit the valve stem 29 and its associated valve body 28 to be slightly tilted. The valve stem 29 projects into the chamber 16 and is adapted to be engaged by the inner end of a flexible diaphragm 30 provided in the chamber 16 and which has its outer side exposed to exterior hydrostatic pressure. Upon inhalation the chamber 16 is exhausted of its fluid so as to reduce the pressure therein and permit the diaphragm to be forced inwardly by the exterior hydrostatic pressure, against the valve stem 29 which in turn tilts the demand valve body 28 into an open position, as shown in Fig. 3, thereby permitting the fluid which is under pressure from the reservoir or container 13 to flow through the flexible conduit 12 into the chamber 16, hence through ports 17 and 18, to the person being served with the fluid. When inhalation ceases the demand valve is moved back into a closed position by a biasing spring 31 associated with the valve stem 29. The biasing spring 31 rests on a base provided by the inner end of the tubular member 21 and tapers toward its outer end until its outermost coil is in close contact with the valve stem 29. The spring 31 normally urges the stem 29 and valve body 28 into a port closing position.

A baffle 32 extends downwardly, as seen in Figs. 2 and 3, toward the valve stem 29 so as to provide a guide or abutment for the valve stem and prohibit the valve stem from moving in an upward direction. The baffle 32 serves the additional function of diverting the incoming fluid flow away from the diaphragm 30 and toward the ports 17 and 18.

The diaphragm 30 consists of a hollow bellows which may expand and contract due to its corrugated surface

consisting of alternate ridges 33 and valleys 34. The outer peripheral contour of the diaphragm is generally rectangular, the two longer sides being parallel to one another and having rounded end portions. The diaphragm is hollow in the center and open at its top while the bottom thereof is completely closed. The bottom is preferably provided with a metal plate 35 having a depending lug 36 which engages the valve stem 29. The diaphragm 30 is entirely contained within the chamber 16 and is adapted to be sealingly secured at its upper end to the housing 10. As seen in Figs. 2 and 3, the housing 10 is provided with a recessed shoulder 37 which extends completely around its periphery. A diaphragm cover member 38 is adapted to have the edge 30a of the open end of the diaphragm slip snugly around its outer edges in such a manner that the diaphragm cover 38, which is adapted to fit snugly within the recessed shoulder 37, snugly compresses the upper edge of the diaphragm between its outer edge and the recessed shoulder 37 so as to provide a water-tight seal between the diaphragm and housing 10. The diaphragm cover 38 is preferably constructed of metal or suitable plastic material and is provided with a plurality of spaced apertures 39. The diaphragm cover protects the diaphragm 30 against damage from foreign objects but still allows the water to pass through its apertures without restriction and subject the diaphragm to exterior hydrostatic pressure. It further acts as a clamping plate to seal the diaphragm 30 tightly to the body 10 and serves as a stop to limit the outward movement of the diaphragm 30.

The metal plate 35 at the bottom of the diaphragm also aids in adding rigidity to the bottom of the diaphragm and causes the diaphragm to expand and contract in a uniform manner. It also functions to exert pressure upon the valve stem 29 at but a single point, that being at lug 36.

The diaphragm 30 normally extends downwardly into the chamber 16 under exterior hydrostatic pressure to an extent wherein it just abuts the valve stem 29, as seen in Fig. 2. Upon inhalation by the user the diaphragm 30 is expanded inwardly due to the decreased pressure in chamber 16 which permits the exterior hydrostatic pressure to push the diaphragm inwardly against the valve stem so as to tilt the valve stem 29 which in turn tilts the demand valve body 28 into a port open position. During inhalation the diaphragm 30 expands from its normal position, as seen in Fig. 2, to that as shown in Fig. 3. As soon as the user ceases to inhale or upon exhalation which increases the pressure in chamber 16, the diaphragm 30 will return to its position, as illustrated in Fig. 2, whereby the inlet port 26 is immediately closed. It will be understood that this particular structure is designed to furnish necessary fluid to the diver on demand with a minimum of effort required for both inhalation and exhalation. The external hydrostatic pressure on the diaphragm 30 aids the diver during inhalation in overcoming the slight pressure exerted upon the valve body 28 by the fluid from container 13.

Valve means are provided whereby the exhaled fluid may be discharged from the device with substantially no resistance. This is accomplished by means of an exhaust or exhalation valve which is located in substantially the same zone and subject to the same exterior hydrostatic pressure as that of diaphragm 30 and the exterior portions of the mouth of the user. The exhalation valve is located in a hollow cylindrical extension 10b located at the left of the housing 10 as seen in Figs. 2 and 3. A fluid outlet port 40 is provided at the junction of the cylindrical extension 10b and the chamber 16 by means of a pair of crossing spoke-like members 41 and 42 having a hub 43 at their intersection. The exhalation valve unit itself consists of a relatively thin circular disc 44 preferably constructed of rubber or other flexible material and having at the center thereof an outwardly projecting portion 45 with an enlarged end portion adapted

to be engaged within an aperture provided in the hub 43. The outer peripheral edge of the flexible valve disc 44 is normally in sealing engagement with a valve seat 46 provided on the downstream face of the outlet port 40. The cross spokes 41 and 42 provide additional support for the flexible valve disc 44 during inhalation. It will be understood that only during exhalation or increased chamber 16 pressure does the outer peripheral edge of valve disc 44 flex outwardly or lift away from valve seat 46 thereby opening outlet port 40 to permit the exhaust fluids to be delivered to the exterior of the device. During inhalation, the flexible valve disc 44 is merely drawn into closer sealing contact with the valve seat 46 and the cross spoke members 41 and 42.

A suitable filter 48 preferably constructed of porous metal, bronze, sponge rubber or foam plastic is provided in the cylindrical extension 10b downstream of the valve 44 and performs the function of protecting the valve 44 as well as filtering the exhaust fluids.

The mouthpiece 11 provides means for holding the self-contained unit in the mouth of the user and at the same time sealing out all water. It is to be understood that the curved arcuate portion 50 is adapted to be placed in the mouth between the teeth and the inner lips while the projecting portions 51 extend between the teeth and are adapted to be grasped by the teeth of the user for retention of the apparatus. The mouthpiece 50 is also provided with a pair of spaced loops or ring members 52 and 53 which are adapted to encircle the body 10, as seen in Figs. 1, 2 and 3 and retain the diaphragm cover 38 in position. A retainer clip 54 extends between the two loop members 52 and 53 and maintains the spacing between the loops to prevent them from becoming accidentally displaced from the body 10.

It should now be apparent that the invention has two major aspects. First, it facilitates the ease of breathing which is made possible by locating the diaphragm and the exhaust valve in the same zone as the mouth of the user, thereby preventing differential hydrostatic head pressure therebetween and subjecting the mouth of the user to the same internal and external hydrostatic pressure when in use thereby permitting relatively effortless breathing by the user of said apparatus. Second, the apparatus is extremely compact with the elements thereof providing a plurality of functions. Thus, by equalizing the three essential pressures, namely the pressure at the diaphragm, the pressure on the mouth, and the pressure at the exhalation valve, it becomes possible to provide uniform effortless breathing at any depth. Unequal pressures, due to a difference of depth between these members causes a differential hydrostatic head pressure which must be overcome by the user while breathing. For natural pressure equalizing, both the diaphragm and the exhalation valve should be in the zone of the mouth at all times as set forth in the present invention. By providing the various components as heretofore described adjacent the mouth it is possible to assure constant equalized pressure at any depth, and under all conditions thereby providing the easiest, effortless breathing possible.

The single, medium-pressure hose or conduit 12 is more durable and less vulnerable to hose damage and allows more freedom than the oversized hoses as used in the past. The present single hose eliminates mouthpiece "pull" due to hose buoyancy, and "water drag" caused by hose bulk and corrugations. It is also less vulnerable to hose fouling, snagging, puncturing, etc. The swivel hose connection permits "self-positioning" of the mouthpiece for most comfort and eliminates cramping in the neck and jaws of the diver.

Due to the small size of the chamber 16 there is no danger of building up a store of carbon dioxide and re-breathing it since substantially all breath is expelled at each exhalation. Through the provision of the present invention, wherein all breathing is done through a mouth-

5
10
15

piece held in the mouth of the user, all face mask mouth-piece and hose cavity rebreathing has been eliminated.

Tests have proven that the pressure on the face is the only noticeable force to be overcome in underwater breathing. The present design has simplified the process of maintaining the same internal and external pressure on the face of the user by locating the diaphragm and exhalation valve in the mouthpiece. The pressure sensitive area as determined by these tests proved that the present unit works equally well in all positions of the swimmer. Prior devices of this type do not maintain the demand valve controlling diaphragm and the pressure sensitive face area at the same pressure head, but permitted a difference to exist in the internal and external pressure on the face which had to be overcome by the exertion of a muscular force by the swimmer.

In Figs. 7 through 11 I have shown still another embodiment of the present invention. The principles employed in this embodiment are similar to those of the first embodiment of the invention, however, the structure has been slightly modified, as explained hereinafter. The main body or housing 60 of the device is circular in form, as seen in Figs. 6 and 7. The diaphragm 61 is constructed of a suitable thin flexible material, such as rubber and consists of a single unbroken disk having an arcuate edge portion 62 which makes the diaphragm more flexible. The diaphragm is generally circular in shape and forms substantially a wall of the chamber 63. The diaphragm is retained by means of a circular cover member 64 which threadedly engages the body portion 60 at 65 to secure the outer peripheral edge 66 of the diaphragm between the body 60 and cover 64, as seen in Figs. 7 and 10.

The undersurface of the diaphragm 61 is provided with a thin supporting plate 70 preferably made of metal or plastic which adds rigidity to the diaphragm and tends to cause the diaphragm to move about the zone 62 which is radially beyond the outer circumferential edge of the plate 70.

The cover 64 is applied to the body 60 over the outer peripheral edge 66 of the diaphragm 61 and is provided with a plurality of spaced openings 67 to permit the exterior hydrostatic pressure to act on the outer surface of diaphragm 61. The cover also acts to protect the diaphragm against foreign objects.

The demand valve body 71 has been somewhat modified and includes a seat engaging member 72 which is adapted to engage the valve seat 73, as seen in Fig. 11. The seat engaging member 72 is rigidly secured to the valve body 71 and positions the valve body 71 a spaced distance from the valve seat 73. The seat engaging member 72 is rigidly secured to the valve body 71 and positions the valve body 71 a spaced distance from the valve seat 73. The seat engaging member is concentric to the valve body member and has a width substantially smaller than the valve body member and just slightly greater than the inlet port 74. The seat engaging member 72 tilts about its outer periphery in response to movement of the diaphragm 61 and thereby very easily opens the inlet port 74, as shown in Fig. 10. The seat engaging member 72 having a smaller area than the valve body member 71 is subjected to less pressure by the air in hose 78 than the valve body 71. Therefore, it requires less force from the diaphragm and valve stem 75 to open the inlet port 74. Thus, upon inhalation by the user, the pressure in chamber 63 decreases and the exterior hydrostatic pressure forces diaphragm 61 inwardly of chamber 63 and causes the valve stem 75, which is preferably merely in bearing contact but may be pivotally secured by any suitable means to the plate 70 to tilt the valve body 71 about a pivot point defined by the outer circumferential edge 76 of the member 72.

After the inlet port has been opened by the seat engaging member 72 pivoting about its outer edge 76, it will be readily understood that a transition occurs wherein the

outer circumferential edge 71a of valve body 71 becomes the pivot point thereby causing the inlet port to be opened much faster and to a greater extent per unit deflection of the valve stem 75 than would be the case if pivoting continued about the point 76 of seat engaging member 72. This is true because the outer circumferential edge 71a is located radially farther away from the valve stem 75 than the outer circumferential edge 76 of the seat engaging member 72. Thus, only a slight movement in the diaphragm 61 is required to provide a somewhat faster and more extensive opening in the inlet port than was possible in the first embodiment of the invention. Coil spring 95 normally biases the valve stem 75 into a valve closed position.

A hollow cup like member 99 is secured to the lower surface of plate 70 with its open end disposed toward the interior of chamber 63. The end of valve stem 75 preferably rests in the cup as shown in Figs. 7 and 10. As the diaphragm deflects inwardly of the chamber 63, it will be readily understood that the outer circumferential edge 99a of the cup will engage the valve stem and thereby shorten the lever arm and cause the valve stem to tilt at a faster rate thereby more quickly opening the inlet port 74.

A universal joint is provided for the connection between the apparatus and the flexible hose 78 which communicates with a fluid source. The universal joint is provided by a ball 80 which is movably secured to a cylindrical extension 60a of the housing 60 by means of a retainer ring 81 which threadedly engages the outer surface of the cylindrical extension 60a at 82. The ring member 81 has an inwardly extending rim 82 adjacent its outer end which provides a circular opening having a smaller diameter than to greatest diameter of the ball 80 and thereby retains the ball within the cap 81. An O-ring 83 is provided to seal the ball and cap against leaks. The ball 80 is provided with an elongated portion 84 and a bore 85 which extends through the ball and also through the elongated portion thereof to provide communication between the inlet port 74 and the flexible hose 78. The hose 78 slips over and snugly engages the elongated portion 84 of ball 80.

The mouthpiece 88, which is constructed substantially the same as that shown in Fig. 1 with the exception of the spaced loops 52 and 53 which are eliminated in the present embodiment because of the cover 64, threadedly engages the body member 60 and the mouthpiece is secured to the body by means of an outstanding flange 90 on body 60. Ports 96 and 97 communicate between chamber 63 and the mouth of the user.

An exhaust or exhalation valve 92 and a filter 93 are provided in the extension 60b of the housing 60 in much the same manner as shown in the first embodiment and in substantially the same zone as the demand or valve body 71 and the diaphragm 61.

The enlarged circular diaphragm 61 is somewhat quicker to respond to decreased or increased chamber pressure due to inhalation and exhalation respectively and thereby when coupled with the high flow, quick opening demand valve body 71 provides a very efficient device. The universal coupling provided by the ball and socket joint also makes the device very easy to maneuver.

In all other ways the second embodiment of the invention is identical in operation and function to that disclosed in Fig. 1.

In view of the foregoing description taken in conjunction with the accompanying drawings, it is believed that a clear understanding of the construction, operation and advantages of the device will be quite apparent to those skilled in this art.

Having thus described my invention and illustrated its use, what I claim as new and desire to secure by Letters Patent is:

1. A breathing apparatus comprising in combination a gas container, a housing having a chamber and a

mouthpiece integrally associated therewith and adapted to be engaged by the mouth of the user, said mouthpiece having an opening communicating between said chamber and the mouth of the user, a single conduit connected between said housing and said gas container, a gas inlet port in said housing communicating with said chamber and said conduit, a demand valve controlling said gas inlet port, a substantially rectangular diaphragm in said chamber having one side thereof exposed to exterior hydrostatic pressure and movable in response to a decrease in pressure in said chamber, said diaphragm having corrugated sidewalls permitting said diaphragm to expand and contract in a bellow-like manner, means operatively associated between said diaphragm and said demand valve causing opening movement of said demand valve in response to expanding movement of said diaphragm, a gas outlet port in said housing in communication with said chamber, an exhaust valve controlling said gas outlet port, said exhaust valve adapted to open in response to an increase in pressure in said chamber, said external hydrostatic pressure being insufficient to cause said diaphragm to open said demand valve, reduced chamber pressure permitting said external hydrostatic pressure to expand said diaphragm thereby causing said demand valve to open, increased chamber pressure causing said diaphragm to contract thereby closing said demand valve and opening said exhaust valve, said chamber pressure being increased or decreased in response to exhalation and inhalation respectively by the user, said diaphragm and said exhaust valve being located in the same zone as the mouth of the user, thereby preventing differential hydrostatic head pressure therebetween and subjecting the mouth of the user to the same internal and external hydrostatic pressure when in use thereby permitting relatively effortless breathing by the user of said apparatus.

2. A breathing apparatus comprising a housing, a mouthpiece integrally associated with said housing and adapted to be engaged within the mouth of the user, a chamber in said housing and disposed in the same zone as said mouthpiece when in use, said mouthpiece having an opening communicating with said chamber and the mouth of the user, a demand valve in said housing controlling the flow of gas from a suitable source into said chamber, a substantially rectangular diaphragm in said chamber, said diaphragm having corrugated sidewalls permitting said diaphragm to expand and contract, said diaphragm having a closed bottom and an open top, said top having its peripheral edges secured to the edges of an opening in the side wall of said housing whereby one surface of said diaphragm is exposed to exterior hydrostatic pressure, a perforated cover for said opening in the side wall of said housing supporting said diaphragm in sealing engagement with said housing, said diaphragm movable in response to pressure changes in said chamber, means operatively associated between said diaphragm and said demand valve causing opening and closing movement of said demand valve in response to movement of said diaphragm, an exhaust valve in said housing controlling the flow of gas out of said chamber in response to pressure changes in said chamber, said chamber pressure being increased or decreased in response to exhalation and inhalation by the user, said diaphragm and said exhaust valve being located in the same zone as the mouth of the user, thereby preventing differential hydrostatic head pressure therebetween and subjecting the mouth of the user to the same internal and external hydrostatic pressure when in use thereby permitting relatively effortless breathing by the user of said apparatus.

3. A breathing apparatus comprising a housing, a mouthpiece associated with said housing and adapted to be engaged within the mouth of the user, a chamber in said housing and disposed in the same zone as said mouthpiece when in use, said mouthpiece having an opening communicating with said chamber and the mouth

of the user, a demand valve in said housing controlling the flow of gas from a suitable source into said chamber, a substantially rectangular diaphragm in said chamber, said diaphragm having corrugated side walls permitting said diaphragm to expand and contract, said diaphragm having a closed bottom and an open top, said top having its peripheral edges secured to the edges of an opening in the side wall of said housing whereby one surface of said diaphragm is exposed to exterior hydrostatic pressure, said diaphragm movable in response to pressure changes in said chamber, means operatively associated between said diaphragm and said demand valve causing opening and closing movement of said demand valve in response to movement of said diaphragm, an exhaust valve in said housing controlling the flow of gas out of said chamber in response to pressure changes in said chamber, said chamber pressure being increased or decreased in response to exhalation and inhalation by the user, said diaphragm and said exhaust valve being located in the same zone as the mouth of the user, thereby preventing differential hydrostatic head pressure therebetween and subjecting the mouth of the user to the same internal and external hydrostatic pressure when in use thereby permitting relatively effortless breathing by the user of said apparatus.

4. A breathing apparatus comprising in combination a gas container, a housing having a chamber and a mouthpiece integrally associated therewith and adapted to be engaged by the mouth of the user, said mouthpiece having an opening communicating between said chamber and the mouth of the user, an inlet member swingably mounted in said housing, a single conduit connected between said inlet member and said gas container, said inlet member being swingably movable with the movement of said conduit and/or housing to thus prevent a crimping of said conduit, a gas inlet port in said inlet

member communicating with said chamber and said conduit, a demand valve controlling said gas inlet port, a substantially rectangular diaphragm in said chamber having one side thereof exposed to exterior hydrostatic pressure and movable in response to a decrease in pressure in said chamber, said diaphragm having corrugated sidewalls permitting said diaphragm to expand and contract in a bellows-like manner, means operatively associated between said diaphragm and said demand valve causing opening movement of said demand valve in response to expanding movement of said diaphragm, a gas outlet port in said housing in communication with said chamber, an exhaust valve controlling said gas outlet port, said exhaust valve adapted to open in response to an increase in pressure in said chamber, said external hydrostatic pressure being insufficient to cause said diaphragm to open said demand valve, reduced chamber pressure permitting said external hydrostatic pressure to expand said diaphragm thereby causing said demand valve to open, increased chamber pressure causing said diaphragm to contract thereby closing said demand valve and opening said exhaust valve, said chamber pressure being increased or decreased in response to exhalation and inhalation respectively by the user, said diaphragm and said exhaust valve being located in the same zone as the mouth of the user, thereby preventing differential hydrostatic head pressure therebetween and subjecting the mouth of the user to the same internal and external hydrostatic pressure when in use thereby permitting relatively effortless breathing by the user of said apparatus.
